UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

LOOM.

Application filed November 16, 1923. Serial No. 675,124.

To all whom it may concern:

Be it known that I, JONAS NORTHRUP, a citizen of the United States, residing at Hopedale, in the county of Worcester and State of Massachusetts, have invented certain new and useful Improvements in Looms; and I do hereby declare the following to be a full, clear, and exact description of the invention, such as will enable others skilled in the art to which it appertains to make and use the same.

The present invention relates to an improvement in weft replenishing looms.

The object of the invention is to improve the construction of weft replenishing looms in order to adapt to pivoted picker stick looms weft replenishing mechanism of the well-known Northrop type. To this end the invention consists in the loom hereinafter described and particularly defined in the claims.

In the accompanying drawings illustrating the preferred form of the invention, Fig. 1 is a plan view of the weft replenishing end 25 of the lay, a portion of the frame being shown in section; Fig. 2 is a section taken on the line 2—2, Fig. 1; Fig. 3 is a front elevation of the weft replenishing end of the lay; Fig. 4 is a plan of the same with the shuttle box removed; and Fig. 5 is a cross-section taken on the line 5—5, Fig. 1.

The illustrated embodiment of the invention is described as follows: The lay 10 is slotted at 11 to afford egress for the exhausted bobbin or the bobbin from which the thread has broken upon replenishment of the shuttle. The lay is provided with a front box plate 12 and a binder 13 pivoted at 14 to the back box plate. The floor of the lay is provided with pivoted floor plates 15 and 16, the front floor plate 15 being pivoted at 17 on the lay, and the back floor plate 16 being pivoted at 18, and both normally held in the position shown in Fig. 2 by the springs 19 and 20, see Fig. 4.

In the ordinary operation of the loom the floor plates occupy the position shown in Fig. 2 and support the picker 21. The picker stick 22 is received in a central opening in the picker, and being pivoted at its lower end instead of being mounted on a parallel motion, as in many looms, its upper end rises through the aperture in the picker when the shuttle is picked. This necessitates providing the box with lips to hold the

picker on the floor of the lay. The lip 23 on the front box plate extends rearwardly over the shuttle, and the lip 24 on the rear box plate extends forwardly over the shuttle and thereby holds the picker from rising when the picker stick throws the shuttle.

When the bobbin is being ejected from the shuttle the picker occupies the position shown in Fig. 1, and it is then necessary to open the swinging floor plates 15 and 16 so as to permit the ejection of the bobbin through the slot in the lay. To this end means are provided for actuating the floor plates. A floor plate actuating slide 30 is mounted in the lay transversely of the same near the bottom, as shown in Fig. 2, and when it is moved in the direction of the arrow 31 its upwardly projecting end 32 engages the projecting arm 33 secured by screws on the end of the back floor plate 16 and moves it out to the position shown in Fig. 4. At the same time a lever 34 pivoted at 35 on a casting secured to the lay is operated by the slide 30, the lateral projection 36 of which engages the lower end of the lever 34 to swing the lever clockwise, as seen in Fig. 2, so as thereby to cause the upper end of the lever 34 to press against the projecting arm 37 secured to the front floor plate 15 to move it forwardly, so as thereby to swing the front floor plate forwardly into the position shown in Fig. 4.

The means for actuating the slide 30 is found in the block 38 which slides vertically on the T-head 39 of a portion of the frame 40 of the loom, the block 38 being pivotally mounted on the bolt 41 secured in the rear end of the lever 42 which is secured to the change shaft 43. The lever 42 is a two-part affair, the rear end being pivoted on the arm 44 by means of the pin 45, and a bolt 46 being provided which passes through a hole in the lever 42 and a slot 47 in the arm 44, so that the position of the arm 42 with respect to the change shaft 43 may be adjusted to present the block 38 to the end of the slide 30 when the change shaft is operated, and then as the lay beats forward the end of the slide 30 strikes the block, and the floor plates are swung open to permit the egress of the exhausted bobbin.

The present invention permits the use of a pivoted picker stick with bobbin changing looms. This is a feature of advantage in the application of weft replenishing mechanism.

to looms, as it enlarges the field of sale of such attachments to include a class of looms not heretofore adapted to receive such attachments.

5. Having described the invention, what is claimed is:

1. A weft replenishing loom of the bobbin changing type having, in combination, weft replenishing mechanism, a picker, a picker stick which extends slidably through the picker, a lay provided with a slot for the picker stick, and means controlled by the weft replenishing mechanism for widening the slot when such mechanism is operated 10 to permit egress of the exhausted bobbin.

2. A weft replenishing loom of the bobbin changing type having, in combination, weft replenishing mechanism, a lay provided with a picker stick slot, a picker stick, a picker, 20 means for supporting the picker to cause the latter to move directly in line with the shuttle during the picking operation, and means controlled by the weft replenishing mechanism for widening the slot in the lay 25 when such mechanism is operated to permit egress of the exhausted bobbin.

3. A weft replenishing loom of the bobbin changing type having, in combination, a lay, weft replenishing mechanism, a pivoted 30 picker stick, the lay being provided with a picker stick slot, and means controlled by the weft replenishing mechanism for widening the slot when such mechanism is operated to permit egress of the exhausted 35 bobbin.

4. A weft replenishing loom of the bobbin changing type having, in combination, a lay, weft replenishing mechanism, a pivoted picker stick, a picker, the lay being provided 40 with a slot under the position occupied by the shuttle during replenishment to permit egress of the exhausted bobbin, a movable floor plate for the lay which normally supports the picker, means connected with the 45 weft replenishing mechanism for actuating the movable floor plate when the replenishing mechanism is operated to remove the floor plate from the path of motion of the exhausted bobbin.

5. A weft replenishing loom of the bobbin changing type having, in combination, a lay provided with a longitudinal slot in its end under the shuttle to permit the egress of the exhausted bobbin, a pivoted picker stick, a

picker, floor plates mounted on the lay to 55 support the picker when the shuttle is picked, means for moving the floor plates to widen the slot in the lay floor to permit egress of the exhausted bobbin, weft replenishing controlling means, and connections between the 60 floor plate actuating means and weft replenishing controlling means operating to move the floor plates when weft replenishment is indicated.

6. A weft replenishing loom of the bobbin changing type having, in combination, a lay, 65 a shuttle box, a shuttle, a bobbin slot in the lay, a pivoted picker stick, a picker, a movable floor plate mounted on the lay for supporting the picker when the shuttle is 70 picked, means for moving the floor plate to open the bobbin slot, weft replenishing controlling means, and connections between the means for moving the floor plate and weft 75 replenishing controlling means operating upon indication of weft exhaustion to move the floor plate to permit the egress of the exhausted bobbin.

7. A weft replenishing loom of the bobbin changing type having, in combination, a lay 80 having a bobbin slot, a pivoted picker stick, a picker, floor plates pivoted on the lay overhanging the sides of the bobbin slot to support the picker when the shuttle is picked, a change shaft, an arm mounted on the 85 change shaft carrying a bunter, a slide mounted on the lay adapted to strike the bunter when the change shaft is operated upon exhaustion of the bobbin, and connections between the slide and the floor plates 90 to swing them apart so as to enlarge the opening at the top of the bobbin slot to permit the egress of the exhausted bobbin.

8. A weft replenishing loom of the bobbin changing type having, in combination, weft 95 replenishing mechanism, a lay provided with a bobbin slot, a pivoted picker stick, a picker, floor plates mounted on the lay normally overhanging the bobbin slot sufficiently to support the picker and afford a passage 100 between them for the picker stick, means controlled by the weft replenishing mechanism for moving the floor plates apart so as to permit the egress of the exhausted bobbin upon the indication of weft re- 105 plishment.

JONAS NORTHRUP.
